UNITED STATES PATENT OFFICE

2,455,764

METHOD FOR GEL MANUFACTURE

Leslie T. Hartlove, Baltimore, Md., assignor to
The Davison Chemical Corporation, Baltimore,
Md.

Application January 22, 1943, Serial No. 473,245

2 Claims. (Cl. 214—1.1)

1

This invention relates to gel and more particularly has reference to the handling of the gel during the manufacturing thereof.

In the manufacture of gel such as a silica gel, a hydrosol which may be formed by the interaction between a solution of a soluble silicate such as sodium silicate and an acid such as sulfuric acid is run into tubs or tanks and allowed to gelatinize or set. One method of handling the gel in this stage of manufacture comprises running a sol formed as above described into a tub which is mounted for inversion so that after the hydrosol has set into a hydrogel, the latter may be removed from the tub by inversion of said tub.

It has been found that in inverting the tub to remove the hydrogel therefrom, there is a tendency for portions at least of the hydrogel to remain in the tub and necessitate an operator scraping the same from the walls of the tub.

An object of this invention is to facilitate the removal of a hydrogel from a tub or receptacle in which it has set.

Another object of this invention is to facilitate the removal of a hydrogel from an invertible receptacle by reducing the adhesion between the hydrogel and the walls of the receptacle.

Still another object of this invention is to facilitate the removal of a hydrogel from a container in which it has set by introducing a fluid into the container at the bottom thereof to reduce the adhesion between the hydrogel and the walls of the container.

With these and other objects in view, the present invention comprises the steps and procedure and the parts in combination hereinafter described and illustrated in the accompanying drawings.

In the drawings:

Figure 1 is a vertical sectional view through an invertible tub in which a hydrogel is set and from which it is removed in accordance with the present invention.

Figure 2 is a plan view of the tub illustrated in Figure 1.

In carrying out the present invention, a hydrosol formed by mixing solutions of sodium silicate and sulfuric acid, for instance, is run into the tub 1 for setting. Tub 1 may be formed of cypress or other suitable wood or other material which will withstand the chemical action of the hydrosol and the wear and tear of handling the same. The tubs may be formed of a plurality of segmental elements which are assembled in the usual manner of forming wooden tubs. A metal band 2 surrounds the outer wall of the tub and serves to retain the parts in assembled relation. Extend-

2

ing radially outwardly from the band 2 at diametrically opposite points are a pair of trunnions 3 which are received in openings provided in the lower ends of a bail 4 which in turn is supported by the carriage 5 of an endless conveyor 6. During the filling operation and while the hydrosol is setting to form a hydrogel, the tub is maintained in an upright position by means of the U-shaped latch 7 which is pivotally carried by the upper rim portion of the tub for swinging movement into and out of engagement with the bail 4.

After the hydrosol has gelled to form a hydrogel and is ready to be discharged from the tub 1, a tube 8 which communicates with a flexible hose 9 is inserted into the open upper end of the tub down through the hydrogel into engagement with the bottom of the tub. Air under pressure is supplied from a suitable source through the flexible hose 9 and is ejected from the lower end of the tube 8. By thrusting the tube 8 down through the gel to the bottom of the tub 1 and causing air to flow therefrom, the air will tend to flow between the contacting surfaces of the walls of the tub and the hydrogel. This action will reduce the adhesion between the hydrogel and the walls of the tub and will split and crack the gel free from the tub, thereby facilitating removal of the hydrogel from the tub. After the injection of air into the tub as above described, the tub may be inverted by releasing the latch 7 and the contents thereof discharged therefrom. The reduction in adhesion between the hydrogel and the inner surface of the walls of the tub enables the body of gel within the tub to be completely removed from the tub upon inversion of the latter without any portions thereof adhering to said tub. In other words, the hydrogel will slip out of the inverted tub substantially in the form of a body.

In following the above outlined procedure for removal of the hydrogel from the tub, scraping or washing of the gel from the surfaces of the inverted tub is eliminated.

From the foregoing description, it will be appreciated that the present invention provides a novel method and apparatus for effecting a simplified and complete removal of a hydrogel from a setting receptacle.

I claim:

1. A method of removing hydrogel from an invertible setting container comprising inserting the discharge end of an air ejecting conduit into said gel and in engagement with the bottom of the container, ejecting air from said conduit to

loosen the adhesion of the gel to the wall of the container, and then inverting the container.

2. A method of reducing the adhesion of a hydrogel with the wall of a setting container comprising inserting the discharge end of an air ejecting conduit into said gel and in engagement with the bottom of the container, ejecting air from said conduit to loosen the adhesion of the gel to the wall of the container.

LESLIE T. HARTLOVE.
